UNITED STATES PATENT OFFICE

107,247

DESIGN FOR A SPECTACLE FRAME

Michael R. McDanal, Denver, Colo.

Application February 13, 1937, Serial No. 67,634

Term of patent 14 years

To all whom it may concern:

Be it known that I, Michael R. McDanal, a citizen of the United States, residing at Denver, in the county of Denver and State of Colorado, have invented a new, original, and ornamental Design for a Spectacle Frame, of which the following is a specification, reference being had to the accompanying drawing, forming part thereof.

In the drawing:—

Fig. 1 is a face view of a spectacle frame showing my new design.

Fig. 2 is a side view thereof.

Fig. 3 is an enlarged detail of the temple hinge attachment.

The essential features of my design reside in the relatively abrupt corner produced by the intersection of the arcs forming the top and outer side of the lens rim in combination with a temple mounting ornamented substantially as shown and positioned on the lens rim so that the angle formed between the side arc and the mounting is substantially a right angle while the one formed between the top of the lens rim and the mounting is a wide obtuse angle.

I claim:

The ornamental design for a spectacle frame, as shown and described.

MICHAEL R. McDANAL.
